UNITED STATES PATENT OFFICE

ARTHUR K. LAUKEL, OF DETROIT, MICHIGAN

ELECTRODEPOSITED PATTERN

Application filed December 3, 1928. Serial No. 323,391.

The present invention pertains to an electrolytically deposited pattern for molding purposes, wherein the molding surfaces of the pattern are reproduced by plating metal such as copper into an impression taken from the body to be reproduced, as disclosed for example in my co-pending application Serial No. 108,715 filed May 13, 1926.

Whereas the electrodeposit might ordinarily be made rather thick, the object of the present invention is to make this deposit of only such thickness as to withstand manipulation in a subsequent reinforcing operation. In other words, the thickness of the metal is such that, without reinforcement, it is not sufficiently strong to withstand manipulation in molding operations in the foundry. The purpose of reducing the thickness of the deposited metal to a minimum is to shorten the time necessary for deposition and to reduce the cost of the finished product, inasmuch as the reinforcing material with which the deposited body or shell is filled, is cheaper than deposited metal. The filling material may consist of a white metal alloy or even a cementitious material, and the shell may be further reinforced, prior to filling, by plating heavier in the corners and by plating ties across points that might otherwise buckle.

The invention is fully disclosed by way of example in the following description and in the accompanying drawings, in which

Figure 1 is a plan view of a mold with the shell deposited therein;

Figure 2 is a plan view of the pattern after being filled with reinforcing material and after levelling of the parting surface;

Figure 3 is a section on the line 3—3 of Figure 2; and

Figure 4 is a section on the line 4—4 of Figure 2.

Reference to these views will now be made by use of like characters which are employed to designate corresponding parts throughout.

In Figure 1 is illustrated a mold 1, which may be made as a plaster cast of the body to be reproduced. The impressed surface of the cast and the margin of the impression

are made conductive in any suitable manner, and the mold is suspended in an electrolytic bath, with the conductive surface wired as a cathode, whereby a deposit 2 is formed on the conductive surface.

The shell is subsequently to be filled with a reinforcing material, and in the interest of a quick plating operation and economy in plating metal, the shell is allowed to grow to only such thickness as will withstand handling during the process of filling. This thickness, however, is not such as would enable the shell to stand up, without reinforcement, in molding operations in the foundry.

It will be seen that the shell is formed with a flange 3 where the mold has been made conductive at the margin of the impression therein. This flange strengthens the shell while it is being filled as will presently be described. Where the shell is likely to buckle in handling prior to filling, it may be provided with ties 4 deposited from wall to wall thereof on conductive bridges inserted in the shell before the plating operation is completed. Also, a heavier deposit may be caused to accumulate in the corners as indicated by the numeral 5 in the various figures, by means of anodes inserted in the corners.

The shell is then filled with a suitable reinforcing material 6, such as a low melting alloy or a cementitious material, either before or after removal from the mold. Cavities 7 may be retained in the filling material at the wider parts of the mold in order to govern the weight of the product and to avoid waste of material.

The parting surface of the filled pattern is now machined off as indicated by the numeral 8. It will be seen by reference to Figure 2 that certain of the ties 4, are practically buried in the filling material after the machining operation, but inasmuch as these ties extend from wall to wall beneath the surface of the filling material, they serve the purpose for which they are provided. The machining operation further removes the flange 3 as may be seen by a comparison between Figures 1 and 2.

The invention has been described in con-

nection with patterns, but the word "pattern" is used in its broad sense, meaning a reproduction of another body for foundry purposes.

5 Although a specific embodiment of the invention has been illustrated and described, it will be understood that various alterations in the details of construction may be made without departing from the scope of 10 the invention as indicated by the appended claims.

Having thus fully described by invention, what I claim as new and desire to secure by Letters Patent is:—

15 1. A metal pattern consisting of a shell of electrolytically deposited metal of insufficient thickness to withstand manipulation in molding operations, and a filling material therein for reinforcing the same, said material being of a character capable of 20 withstanding high production molding operations.

25 2. A split metal pattern consisting of a shell of electrolytically deposited metal of insufficient thickness to withstand manipulation in molding operations, and a filling material therein for reinforcing the same, said material being of a character capable of 30 withstanding high production molding operations, said shell and reinforcing material being machined at the parting surface.

35 3. A metal pattern consisting of a thin shell of electrolytically deposited metal, a filling material therein for reinforcing the same, said material being of a character capable of 40 withstanding high production molding operations and ties of deposited metal across said shell at selected points thereof.

45 4. A metal pattern consisting of a thin shell of electrolytically deposited metal, said shell being thicker in the corners, and a filling material in said shell for reinforcing the same, said material being of a character capable of 50 withstanding high production molding operations.

55 5. A metal pattern consisting of a shell of electrolytically deposited metal of insufficient thickness to withstand manipulation in molding operations, ties of deposited metal across said shell at selected points thereof, and a filling material in said shell for reinforcing the same, said material being of a character capable of 60 withstanding high production molding operations.

65 6. A metal pattern consisting of a shell of electrolytically deposited metal of insufficient thickness to withstand manipulation in molding operations, said shell being relatively thicker in the corners, and a filling material in said shell for reinforcing the same, said material being of a character capable of 70 withstanding high production molding operations.

7. A metal pattern consisting of a thin shell of electrolytically deposited metal, and a filling material therein for reinforcing the same, said material being of a character capable of 75 withstanding high production molding operations, said filling material forming cavities in the wider parts of said shell.

8. A metal pattern consisting of a thin shell of electrolytically deposited metal, a filling material therein for reinforcing the same, said material being of a character capable of 80 withstanding high production molding operations, and ties of deposited metal across said shell at selected points thereof, said filling material forming cavities in the wider parts of said shell.

9. A metal pattern consisting of a shell of electrolytically deposited metal of insufficient thickness to withstand manipulation in molding operations, and a poured metal filling material therein for reinforcing the same, said metal being of a character capable of 85 withstanding high production molding operations.

In witness whereof I have hereunto set my hand.

ARTHUR K. LAUKEL.
